UNITED STATES PATENT OFFICE.

JOSIAH SWETT, OF GRANVILLE, AND GEORGE W. BRACE, OF SOUTHWICK,
MASSACHUSETTS.

LAMP AND LANTERN ATTACHMENT.

SPECIFICATION forming part of Letters Patent No. 349,765, dated September 28, 1886.

Application filed December 19, 1885. Serial No. 186,145. (No model.)

To all whom it may concern:

Be it known that we, JOSIAH SWETT and GEORGE W. BRACE, citizens of the United States, residing, respectively, at Granville and 5 Southwick, in the county of Hampden and State of Massachusetts, have invented new and useful Improvements in Lamp and Lantern Attachments for Carriage-Shafts, of which the following is a specification.

10 This invention relates to improvements in lamp and lantern attachments for carriage-shafts, the object being to provide improved devices for supporting a lantern or coach-lamp on a carriage-shaft in advance of the 15 carriage at the side of the horse, whereby the light therefrom will be thrown farther forward than it is when the lamp is attached to the carriage in the usual way.

In the drawings forming part of this specification, Figure 1 is a front elevation of a lantern-support embodying our improvements, showing a lantern suspended thereon and the carriage-shaft in cross-section within the bracket by which the latter is secured to said shaft. Fig. 2 is a rear perspective view of the 25 lantern-supporting devices, the lantern being removed therefrom. Figs. 3 and 4 are detail parts, which are fully described below.

In the drawings, A indicates a section of a 30 carriage-shaft, and B is a clamp-bracket secured on shaft A, to which the said support and lantern or lamp are suspended. The said clamp-bracket consists of two metallic shells, c', of suitable form to clasp and fit onto the opposite sides of the shaft of a carriage, and to encircle, or nearly so, said shaft when secured thereto, as shown in Fig. 1. Said bracket-shells are hinged together at x, and the lower one, c, is provided with an arm, d, the end of 35 which is reduced and made round, and a nut, v, is screwed onto it.

Fig. 3 is a view of a part of the side of the clamp-bracket B, from which the arm d projects, looking directly at the end of the latter, 45 nut v being removed, thereby furnishing an unobstructed view of that part of said arm or the end of the latter back of its said reduced part, wherein are set a series of projecting pins, z, whose purpose is described below. 50 The upper one, c', of said bracket-shells has an arm, e, thereon extending over the upper

side of the said arm d, as shown, in which is a thumb-screw, o, which screws into the latter arm, and thereby the said shells are clamped and locked on the shaft A, and are conveniently released to allow of opening them to remove them from said shaft. The end of the arm e terminates at that part of arm d in which the said pins z are fixed.

The part of the device to which the lantern or lamp is directly attached consists of rectangular flat metallic plate h, having an arm, i, thereon, which is perforated to receive the rounded end of the arm b of said clamp, and is provided with perforations f to receive the 65 ends of the pins z on the arm d.

Fig. 4 is a face view of the side of arm i, which in practice is brought against the said end of arm d when the nut v is screwed against it.

The above-described pins z and perforations f provide for swinging the plate to different inclines on arm d and then engaging said pins in the holes f, thereby firmly retaining said plate in said inclined position without danger 75 of its swinging back to a vertical one; and, furthermore, said pins and holes serve to hold plate h firmly in a vertical position after nut v is screwed against the side of arm i.

The purpose of providing means for maintaining the plate h in other than a pending vertical position is, that it may be desirable during deep snows, or under other circumstances, to swing the plate upward. The plate h has secured thereon centrally, as shown 85 by dotted lines in Fig. 2, a projecting hook-strap, of the usual form, to receive a hook on the rear side of the reflector J, and near the upper edge of plate h are secured two lantern-hooks, K K, which project far enough beyond the side of said plate to hook under the upper ends of the tubular part of the lantern H, as shown in Fig. 1, and near the lower edge of plate h are secured two other lantern-hooks, D D, which engage with the lower part 95 of said tubular portion of the lantern H. Said hooks K are bent upward and are flexible, and the hooks D are likewise flexible and bend downward, and normally occupy the positions shown in Fig. 2, but when engaged with 100 the lantern, as in Fig. 1, are sprung up to about the position shown by dotted lines in

Fig. 2, thereby securing an action of said hooks against the said tubular part of the lantern in opposite directions, and obviating any danger of the disengagement, accidentally, of the lantern from the hooks.

Fig. 1 shows the position of the lantern secured to plate *h* in front of the reflector *J*.

When it is desirable to use an ordinary coach-lamp on the plate *h* instead of the lantern, the reflector is removed and the usual hook on the rear side of the lantern is engaged with said hook-strap on the plate by which the reflector is hung on the latter.

The pins *z* may be omitted from the arm *d*, and the perforations *f* from the arm *i*, if desired, letting the sole dependence for holding plate *h* in proper position be upon the nut *v*.

The clamp-bracket *B* may be secured at any desired position on the shaft *A*, or it may be permanently secured thereto, as it does not project laterally far enough to be inconvenient, and the lantern-plate *h* may be left on the bracket or removed at pleasure.

What we claim as our invention is—

1. In combination, the hinged clamp-bracket *B* to clasp the shaft of a carriage, having thereon the arm *d*, the plate *h*, having at one side the perforated arm *i* thereon, by which said plate is attached to said arm *d*, the re-

flector *J*, attached to the side of the plate *h*, and the upwardly-turned lantern-hooks *KK*, and the downwardly-turned lantern-hooks *DD*, secured to and projecting from the side of said plate, substantially as set forth.

2. The combination of the plate *h*, having the lantern-hooks *KK* and *DD* thereon, and the arm *i*, projecting from one corner and provided with the perforations *f*, and the clamp-bracket *B*, having the arm *d*, to which said plate is suspended, in which are fixed the pins *z*, to engage with said perforations *f*, all as set forth.

3. The clamp-bracket *B*, consisting of the shell *c*, having the bracket-arm *d* thereon, the shell *c'*, hinged to shell *c*, and having the arm *e*, through which a screw passes into said arm *d*, combined with the plate *h*, suspended on said arm *d* by means of its arm *i*, projecting from one corner, and provided with the flexible lantern-hooks *KK* and *DD*, to engage with the upper and the lower part of the lantern, substantially as set forth.

JOSIAH SWETT.
GEORGE W. BRACE.
